[57] CLAIM

The ornamental design for a paper support rack for a portable commode.

DESCRIPTION

FIG. 1 is a front, top right side perspective view of a paper support rack for a portable commode, showing my new design;

FIG. 2 is a front view thereof;

FIG. 3 is a bottom view thereof;

FIG. 4 is a left side view thereof; and,

FIG. 5 is a back view thereof.

The broken line showing is for illustrative purposes only and forms no part of the claimed design.
